UNITED STATES PATENT OFFICE.

JOHN R. MORRIS, OF MARSHALLTOWN, IOWA.

WRENCH.

No. 895,285.

Specification of Letters Patent.

Patented Aug. 4, 1908.

Application filed October 7, 1907. Serial No. 396,303.

To all whom it may concern:

Be it known that I, JOHN R. MORRIS, a citizen of the United States, residing at Marshalltown, in the county of Marshall and State 5 of Iowa, have invented certain new and useful Improvements in Wrenches; and I do declare the following to be a full, clear, and exact description of the invention, such as will enable others skilled in the art to which it apper- 10 tains to make and use the same.

This invention has relation to new and useful improvements in wrenches, and has for its object the production of a simple and economical device of this character adapted 15 to be readily and easily adjusted to meet all requirements.

A further object of the invention is to provide the wrench with an adjustable handle which may also be employed as a wrench.

20 In the accompanying drawings: Figure 1 is a side elevation of a wrench constructed in accordance with the invention with parts broken away to more advantageously illustrate the invention. Fig. 2 is a cross section taken on the line 2—2 of Fig. 1. Fig. 3 is a 25 view in side elevation of a modified form of the invention, parts broken away to more advantageously illustrate the invention; and Fig. 4 is a cross section taken on the line 4—4 30 of Fig. 3.

Referring to the accompanying drawings, which are for illustrative purposes only, and therefore not drawn to any particular scale, 1 indicates the wrench body. Said body is 35 provided at one end with a fixed jaw, 2, and in each side with a longitudinal depression or recess, 3.

4 indicates a jaw arranged to slide under the body of the wrench, said jaw having two 40 oppositely disposed side flanges or members, 5, adapted to embrace opposite sides of the body, said member constituting a guide. Said jaw, 4, is held in adjustable position by screws, 6, arranged to work through the side 45 flanges or members of the same, and engage in the depressions or recesses, 3, of the wrench body. Said jaw 4 may be adjusted to suit all requirements by a longitudinally disposed screw, 7, screwing into a correspond- 50 ing screw threaded socket in the body of the same. This screw is provided at its outer end with a nut, 8, for turning it, said nut having a stem or extension, 9, extending from one face and fitting in a corresponding socket 55 10 of a depending member, 11, depending from the wrench body, near the outer ends

of the depressions or recesses, 3. The body of the wrench is prolonged or extends some little distance beyond the depending member, 11, such prolongation constituting a handle, 60 12, the outer end of which terminates in alligator jaws, 13, one of which is provided with inclined teeth, 14, to enable it to securely grip an object.

In the modification of the invention, the 65 handle comprises two independent members, namely, an upper and lower member, 15 and 16, respectively, the upper member being formed by a prolongation of the wrench body, and the lower being hinged to the 70 wrench body adjacent the inner end of the upper member. Each of said members is provided with a plurality of recesses or depressions 17, adapted to register and form eyes when they are in contiguous relation, 75 adapted to receive thread cutting dies, (not shown). The lower or hinged member, 16, may be adjusted relatively to the other handle member by an adjusting screw, 18, working through a corresponding aperture in the 80 hinged member, and screwing in a screw threaded aperture in the fixed member.

Having thus described my invention, what I claim as new and desire to secure by Letters-Patent, is:

85 In a wrench a shank having a fixed jaw at one end and oppositely disposed longitudinal grooves on the sides thereof, a longitudinally perforated lug on the front edge of said shank an adjusting screw having a reduced cylindrical extension closely fitting the perforation whereby said screw is held in parallelism with said shank, means to hold said screw against movement towards said fixed jaw, a movable jaw mounted to slide longitudinally 90 of said shank and having a threaded bore therein adapted to receive said screw, the distance from the forward end of said screw to the face of said fixed jaw being greater than the length of said movable jaw, said 100 movable jaw consisting of a body portion having backwardly projecting spaced flanges embracing said shank, said spaced flanges being terminated slightly to the rear of said longitudinal groove, said flanges being provided with threaded perforations registering with said groove, and stub screws in said 105 threaded perforations and adapted to engage in said grooves, said stub screws being adapted to be disengaged from said longitudinal grooves without removing said stub screws from said threaded perforations,

whereby when said movable jaw is carried beyond the end of said longitudinal screw, said movable jaw may be quickly separated from said shank, said longitudinal screw being constrained to remain in connection with said shank and said stub screws remaining in said threaded perforations.

In testimony whereof I have hereunto set my hand in presence of two subscribing witnesses.

JOHN R. MORRIS.
